UNITED STATES PATENT OFFICE

2,325,636

SHAVER

Samuel Solomon, Union City, N. J.

Application July 25, 1940, Serial No. 347,394

4 Claims. (Cl. 30—41)

This invention relates to new and useful improvements in an attachment for electric or mechanical shavers for preventing the escape of cut hair or hair dust.

The invention is particularly intended for those mechanical razors having interengaged hollow cutting members with open ends. The invention proposes a novel arrangement for temporarily closing these open ends so as to prevent the cut hair or hair dust from falling out during the shaving operation and littering up the sink or other place where one is shaving.

More specifically the invention proposes the provision of frames mounted upon the razor, across the open ends and an arrangement by which the frames support cover plates, or other members, arranged to be readily removed and replaced so that the open ends of the razor may be closed, or opened as desired.

The invention proposes a construction, whereby the frame may be mounted upon the stationary cutting member of the razor, or upon the stationary body of the razor, or upon other portions.

Still further the invention proposes the construction of an attachment as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure—

Fig. 1 is a fragmentary elevational view of the blade end of an electric razor constructed in accordance with this invention.

Fig. 2 is an end elevational view of Fig. 1 looking from the left hand end.

Fig. 3 is a fragmentary vertical sectional view taken on the line 3—3 of Fig. 2.

Fig. 4 is a fragmentary elevational view of an electric razor provided with an attachment constructed in accordance with a modification of this invention.

Fig. 5 is a fragmentary horizontal sectional view taken on the line 5—5 of Fig. 4.

Fig. 6 is an end elevational view similar to Fig. 2 but illustrating another modified provision.

Fig. 7 is a fragmentary vertical sectional view taken on the line 7—7 of Fig. 6.

The attachment for electric shavers to prevent the escape of cut hair or hair dust in accordance

with this invention, is used in combination with an electric or mechanical razor 10 having a pair of interengaged hollow cutting members 11 and 12 with open ends. Razors of this type are old and generally known, and therefore further details thereof will not be given in this specification. In accordance with this invention means is provided for temporarily closing the open ends of the said hollow cutting member 11.

The means referred to in the previous paragraph includes a frame 14 mounted on the razor, across each of the open ends thereof. This frame 14 is formed from two sections. There is a base section 14^a which is attached by several fastening elements 15 to the base portion of the stationary member 11, or to some other stationary or other portion of the razor. There is also an outer section 14^b which is attached to the base section 14^a by several fastening elements 16. 10 Along the bottom portions, the sections 14^a and 14^b are in contact with each other. However, along the top portions, specifically at the sides of the open ends of the hollow member 11, the frame sections 14^a and 14^b are slightly separated, forming a slot 17. A plate 18 is removably mounted in this slot 17 across the open portion of the frame. This plate 18 has beaded edges 18^a along its two sides and its top.

When the plates 18 are in position, the open ends of the hollow cutting member 11 is temporarily closed so that all hair or hair dust will be retained inside of the hollow member. When it is desired to empty and clean the razor, then the plates 18 are removed. This may be done by gripping one of the beaded portions 18^a with the finger nails and then pulling the plate from its position. The plates 18 are frictionally held in the slots 17.

In Figs. 4 and 5 a modified form of the invention has been disclosed, distinguishing from the prior form in the way in which each frame is mounted upon the razor. In accordance with this form of the invention the base section 14^a of the frame 14 is provided with a pair of side lugs 20 which extend over the side portions of the razor 10. As illustrated, the lugs 20 are extending over the side portions of the stationary member 11. Each lug 20 is formed with a small projection 21 which engages into a complementary niche formed in the razor, see Fig. 5.

In other respects this form of the invention is identical to the previous form and identical parts may be recognized by the same reference numerals.

This form of the invention is used in the same

way as the prior form, however, the advantage of this construction resides in the fact that the frames 14 may easily be removed from the razor, when this is desired. To remove the frames 14 it is merely necessary to grip them and pull laterally until the lugs 20 flex, and the projections 21 disengage from their complementary niches.

In Figs. 6 and 7 another form of the invention has been disclosed which is distinguished from the prior form in the construction of each of the frames that is used to close the open ends of the razor. In accordance with this form of the invention, each frame 14' is composed of a base section 14^a which is attached by several fastening elements 15 to the razor. The frame 14' is also provided with an outer section 14^{bb} which is connected with the base section 14^a by a hinge 24 along the bottom edge of the sections. A spring 25 is coaxially mounted upon the hinge 24 and acts between a stationary part and the outer section 14^{bb} for urging the outer section into its closed position.

More specifically, the spring 25 has an end 25^a which engages against the body of the razor 10. The other end 25^b of the spring engages against the outer section 14^{bb}. The plate 18 is removably mounted between the frame section 14^a and 14^{bb}. This plate has a bead 18^a along its edges. The feature of this construction resides in the fact that the resiliency of the spring 25 is depended upon to force the outer section 14^{bb} towards the base section 14^a for tightly gripping and holding the plate 18.

In other respects this form of the invention is like the prior form and the same parts may be recognized by the same reference numerals.

It is to be understood that this device may be of any suitable material and may be attached on electrical or mechanical razors of several kinds.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. In combination with an electric razor hav-

ing a pair of interengaged hollow cutting members with open ends, means for temporarily closing each end, comprising a frame mounted on the razor and across the open end, a plate removably mounted in said frame and across said end, and clips mounted upon said frame and engaging portions of said razor for mounting the frame upon the razor.

2. In combination with an electric razor having a pair of interengaged hollow cutting members with open ends, means for temporarily closing each end, comprising a frame mounted on the razor and across the open end, a plate removably mounted in said frame and across said end, said frame having a base section permanently on said razor, and also having an outer section hingedly mounted on said base section, resilient means for urging said sections together, and said plate being mounted between said sections.

3. In combination with an electric or mechanical razor having a pair of interengaged hollow cutting members with open ends, means for temporarily closing each end, comprising a frame mounted on the razor and across the open end, a plate removably mounted in said frame and across said end, said frame having a base section permanently attached on said razor, and also having an outer section hingedly mounted on said base section, resilient means for urging said sections together, and said plate being mounted between said sections, said resilient means comprising a spring coaxially mounted on the hinge point of said sections and acting to resiliently urge the sections towards each other.

4. In an electric razor having interengaged hollow cutting members with open ends, a substantially rectangular frame for each of said open ends fixedly mounted on said razor over said open ends, each of said frames having an opening aligned with its respective open end and a slot extended inwards from its free end a distance substantially equal to the depth of said opening, and a plate frictionally removably engaged into the slot of each of said frames closing the openings in said frames to close the open ends of said blades, and a beaded edge formed on the exposed edges of said plate and engaging the edges of said frame to prevent relative lateral movement of said plates relative to said frames.
